UNITED STATES PATENT OFFICE.

THOMAS E. BROWN, OF NEW YORK, N. Y.

CENTRIFUGAL MACHINE.

1,215,337.

Specification of Letters Patent. Patented Feb. 13, 1917.

Application filed April 22, 1914. Serial No. 833,841.

To all whom it may concern:

Be it known that I, THOMAS E. BROWN, a citizen of the United States, and a resident of the borough of Manhattan, in the 5 county of New York and State of New York, have invented certain new and useful Improvements in Centrifugal-Machines, of which the following is a specification.

This invention relates to improvements in 10 the art of centrifugal separation, and as well to the process or method as to the apparatus.

The invention applies particularly to the continuous centrifugal separation of solids 15 and liquids and to the apparatus used for the said separation of solids from liquids, as in the filtration and decantation of precipitates in chemical processes, the separation of valuable liquids from the pulp in 20 metallurgical processes, and the clarification of liquids in general; and the object of my invention is to enable various steps in such processes, such as sealing of the bowl, filtration or decantation, drying and washing, 25 and the final discharge of the concentrates, to be performed while the machine remains in continuous revolution, thereby avoiding the wear and tear, loss of power and waste of time incident to the continual starting 30 and stopping of the machine, usual in ordinary practice.

Another object of my invention is to perform the steps automatically in proper succession at suitable intervals of time. The 35 means I employ to effect these objects is the pressure on a fluid, preferably distinct from the liquid undergoing separation, and which pressure may be induced by the rotation of the machine itself or by some external means, or by a combination of both; and I prefer to use a liquid which is suitable 40 for the lubrication of the bearings of the machine.

Various forms of apparatus may be constructed embodying my invention and suited to 45 various kinds of material and to various operations, and while I show some of these forms in the accompanying drawings, I do not confine myself to the specific forms 50 shown and described.

In all the forms of machines illustrated in the said drawings separating vessels revolving on vertical axes are shown, but obviously in all the separating vessels could 55 be arranged to revolve on horizontal axes.

Figure 1 of said drawings, shows a form of apparatus in broken vertical section, which I prefer when the solid material to be treated is granular or crystalline, and is pervious to the liquid from which it is to be separated, and especially when such material is to be washed or treated with other liquid or liquids different from that from which it is to be originally separated, and Fig. 1^a is a broken vertical section on larger 60 scale of certain parts of the machine.

Fig. 2 shows the form of apparatus, in broken vertical section, which I prefer when a solid is to be separated, which is permeable to the containing liquid only with 70 difficulty, and when a process of centrifugal separation partaking of the nature of decantation rather than of direct filtration is desirable and also when a wash treatment is not essential; Fig. 2^a being a broken 75 vertical section on larger scale of certain parts of the machine.

Fig. 3, shows a form of centrifugal apparatus, in broken vertical section, which I prefer to use for the clarification of liquids, 80 where usually the bulk of liquid is large in comparison with the contained solids, and a bowl is necessitated of comparatively large diameter to obtain the necessary large filtrating capacity, and especially where a 85 granular filtering medium, such as sand is employed; Fig. 3^a being a vertical section on an enlarged scale of certain parts of the machine.

Fig. 4, shows an elevation and Fig. 5 a 90 plan of a timing apparatus suitable for the operation of these various forms, and which is particularly described in connection with Fig. 3.

Fig. 6, is a section and elevation of a 95 machine without filter or bowl cover.

Referring to Fig. 1, 1 is a base and 2 a frame supporting the bearings 3 and 4 and thrust bearing 5 of the spindle 6 of the rotating machine, said spindle 6 being revolved in 100 said bearings by any suitable means such as pulley 7 and belt 8. 9 indicates the bottom and inner side of the bowl or separating vessel attached to and revolving with spindle 6, and 10 is the casing of the bowl supported by said bottom 9, (which said bottom 105 may be integral with a vertical inlet pipe 9^a), preferably having a stuffing box 150, to connect with supply pipe 21. Said casing 10 carries the screen or filter 11, which 110

preferably consists of perforated metal plates 12, Fig. 1^a, containing between them a suitable filtering material 13. 19 is a rim fastened to said casing 10 and holding the filter 11 in place. The lower part of said casing 10 is preferably smooth on the inner side, forming a cylinder containing an annular piston 14 attached to or preferably being a part of an inner vertically movable cylinder 15; the upper part thereof flares and projects inwardly. Said cylinder 15 forms a movable bottom to the separating chamber, and carries by means of the rib 16, the cover of the bowl 17. An elastic packing 18 is inserted between said cover 17 and the rim 19 of said casing 10. Said packing 18 may be attached either to the rim 19 or the cover 17, and I prefer, and have shown it attached to the cover 17. 31 is a supply pipe 15 for the mixture to be separated, and 21 is a supply pipe for the operating liquid. 22 is an annular stationary trough for the reception of the separated liquid and 23 is a pipe to carry off said liquid. 25 is an annular stationary trough for the reception of the operating liquid and 26 is a pipe to carry off said operating liquid. 27 is an annular rotary trough for the reception of the discharged concentrates, which is preferably 20 supported on rollers 28 and caused to revolve slowly by any suitable means as belt 29. From said annular trough 27, the said discharged concentrates may be removed in any suitable manner as by scraper 30. 20, 33 and 34 are valves; and 20^E, 33^E and 34^E are electrically operated valves which are preferably provided for purposes of automatic operation of the machine, as will be herein-after explained.

40 The machine having been set in motion and revolving at normal speed before the mixture which is to be separated is admitted to the machine, and the piston 14 and cover 17 being held in lower position by 45 their own gravity, the operation is as follows; it being assumed for the present that said electric valves 20^E, 33^E and 34^E are open.

50 Valve 20 is opened slightly, admitting the operating liquid, which passes down pipe 9^a and through the passages 36 to the inner side of cylinder 15. The centrifugal force generated by the revolution of the machine carries this operating liquid down the inner side 55 of said cylinder 15 and through the openings 37, of which there are preferably several, to the annular space between said cylinder 15 and said casing 10, said liquid being prevented from passing directly to the underside of piston 14 by the cupped piston flange 38. Said operating liquid, after passing through said passages 37, builds itself up in a cylindrical form on the inner surface of casing 10 until the inner surface of said 60 liquid reaches the overflow passages 39, of

which there are preferably several arranged at uniform intervals around the piston 14. Any surplus overflowing through said passages 39 escapes through small leakage holes 40, of which there are preferably two arranged diametrically opposite in said bottom 9. (See also Fig. 1^a). The supply of operative liquid through valve 20 may now be shut off, but a little may be continually admitted to provide for any leakage through 75 the packing 41, but such amount must not exceed what will freely flow through the leakage passages 40.

80 The cylinder of liquid in the said annular space between movable cylinder 15 and casing 10 exerts great pressure on the said piston 14, holding down said cylinder 15 and also, by means of ribs 16, the cover 17, and compressing the packing 18 to the necessary extent to prevent the materials to be separated from passing through the joint between said cover 17 and said rim 19. Said pressure is proportional to the difference of the fourth powers of the inner and outer radii of the cylinder of operating liquid between casing 10 and cylinder 15 and to the specific gravity of that liquid; and by choosing a suitable diameter for casing 10 and for the circle of passages 39 any desired pressure may be obtained.

95 Said bowl being now sealed by the pressure on piston 14, the valve 33 is opened to admit a proper supply of the mixture to be separated through pipe 31 to the said bowl, inside of the filter 11. By reason of the 100 pressure induced by the centrifugal force the liquid portion of said mixture passes out through said filter 11, and thence by the outlet nozzles 42, of which there are preferably at least two, into said rotary trough 22, and 105 is carried away by pipe 23. The solid portions of the mixture are retained by and accumulate on the said filter 11. The mixture undergoing separation is prevented from 110 passing into the lower portion of casing 10 and mixing with the operating fluid by the packing 43.

When a sufficient quantity of the solids 115 has been accumulated on said filter 11, said valve 33 is closed, and a sufficient time is allowed to elapse for liquid retained in the spaces between the crystals or grains of the 120 solids to pass off through said filter 11, and for the solids to attain the desired state of dryness. Valve 34 is then opened and wash liquid is admitted to said bowl. Said wash liquid passes through the solid materials on the filter 11, and through said outlet nozzles 42 to said trough 22, and is carried off by pipe 23 in the same manner as the previously 125 separated liquid, and the wash liquid may be returned to its original source by means of valves and branch pipes from pipe 23 and a suitable pump. When the solid materials have been suitably washed valve 34 is closed 130

and the material is allowed to become sufficiently dry. Successive washes by different liquids may of course be used, if desirable.

When the treatment above described is finished, valve 20 is opened sufficiently wide to admit operating liquid faster than will flow out through said leakage holes 40. The operating liquid then gradually fills the space below said piston 14 and the space 10 between said cylinder 15 and said bottom 9, causing a great upward pressure by reason of the centrifugal force and lifting cylinder 15 and cover 17. The said cylinder 15, which fits closely inside of said filter 11, 15 forces the concentrated solids upward and over the rim 19, whence they are thrown by centrifugal force into the said slowly revolving trough 27, and said solids are removed therefrom by scraper 30, or in any 20 other suitable manner.

Usually with this form of apparatus, the centrifugal pressure alone in the operating liquid under cylinder 15 will be amply sufficient to eject the accumulated solids, but 25 in case of refractory materials which pack very solidly on filter 11 the valve 20 may be opened wide and the full pressure in pipe 21 admitted to underside of cylinder 15 in addition to the said centrifugal pressure.

30 When the solids have been discharged, the supply of operating liquid through said valve 20 is decreased to less than will escape through said leakage holes 40, the liquid under said cylinder 15 and piston 14 escapes 35 and the cylinder of liquid over said piston 14 gradually forms and presses the said piston down, together with said cylinder 15, ribs 16 and cover 17, and compresses the packing 18 and seals the bowl, and the entire process is repeated as before described.

The operating liquid escaping from said holes 40 is caught in said trough 25 and conveyed away by pipe 26. Said operating liquid, if of no value, may be run to waste, 45 but if of value may be returned from pipe 26 to its original source by any suitable means such as a pump; and I prefer to use a liquid suitable for the lubrication of the bearings of the machine, such as oil, and in 50 this case, passages 45 are continued downward in spindle 6, as indicated by dotted lines, and with small outlets to upper bearing 3. When valve 20 is opened sufficiently a portion of the operating liquid passes 55 down and is forced through said passages 45 and through perforations in bearing 3 and is absorbed by the cotton waste in bearing 3. The liquid escaping from bearing 3 is thrown by ring 46 into chamber 47 and 60 passes by pipe 48 to chamber 50 and lower bearing 4, and thence by branch pipe 49 to pipe 26. Branch pipe 49 is preferably placed above the bottom of chamber 50 so that bearing 4 always runs in a bath of oil.

65 Referring to Fig. 2, the filter 11^a is placed

in the cover 17^a of the bowl 10^a, and as the piston 14^a passes over the smooth surface of the casing or bowl 10^a, the piston packing 41^a may replace packing 43, shown in Fig. 1, which packing is therefore omitted. Cored 70 passages 51 in piston 14^a connect inside of packing 41^a so that some of the operating liquid always presses by its centrifugal force said packing 41^a against the surface of bowl 10^a, and prevents the operating liquid from 75 passing from lower to upper side of said piston 14^a, and likewise prevents the mixture undergoing separation from passing said piston 14^a in the reverse direction. In the cylinder 15^a, forming part of piston 14^a, 80 and forming a movable bottom in the bowl, is placed a stuffing box 52, connecting it with pipe 21^a. The leakage holes 40^a are placed in the ends of trapped pipes 56, of which there are preferably two placed diametrically opposite each other. A hollow 85 stem 57 is attached to and projects downward from piston 14^a and works loosely in spindle 6, to form a guide to said piston 14^a. The filter 11^a is shown in a plane perpendicular to the axis of rotation, but may be placed in an inclined position if preferred, and such that the tendency of the centrifugal force is to carry the solid particles away 90 from the filter surface.

95 The operation of this form of machine is as follows:—

Before starting the revolution of the bowl, valve 20^a is opened until the inflow of operating liquid is greater than the outflow 100 through leakage holes 40^a, and the spaces in stem 57 and below piston 14^a are gradually filled with the liquid, the contained air gradually passing out through the passages 36^a and pet cock 53 as the liquid enters. When the contained air is expelled the valves 20^a and pet cock 53 are closed and rotation of the bowl is started. As the speed increases the centrifugal force causes some of the liquid under piston 14^a 110 to pass out through said trapped pipes 56 and leakage holes 40^a until a vacuum is formed under said piston 14^a, and the remaining liquid balances atmospheric pressure at said leakage holes 40^a. The atmospheric pressure on top of said piston 14^a, 115 holds said piston down with great force, and through the ribs 16^a and bolts 58, also holds down the cover 17^a, compresses the packing 18^a and seals the bowl.

120 The mixture to be separated is now admitted by valve 33^a and pipes 31^a and flows into said bowl 10^a under said filter 11^a. The solids are deposited against said bowl 10^a and are compressed by the centrifugal force, the liquid remaining nearer the center of rotation and gradually decanting upwardly 125 through the filter 11. As the solids accumulate, gradually filling said bowl, the liquid passes through the still exposed portions of 130

the filter. The separated liquid, after passing through said filter 11^a passes out through the outlet nozzles 42^a and is caught in revolving trough 24^a, passes by pipes 59 through revolving trough 27^a to stationary trough 22^a and is carried away by pipe 23^a.

When a sufficient quantity of solids has been accumulated said valve 33^a is shut, and after such time as is necessary to dry the material as much as its character will permit, valve 20^a is opened sufficiently to allow more liquid to flow in than will discharge through leakage holes 40^a, the vacuum is destroyed, and the pressure rises under piston 14^a lifting said piston and filter 11^a and cover 17^a. The solids concentrated in the bowl are lifted by piston 14^a until thrown by the centrifugal force into said revolving trough 27^a, from which they may be removed in any suitable manner. When the solids have been discharged valve 20^a is again closed, a vacuum is formed under said piston 14^a, as before described, said piston descends with said cover 17, compresses the packing 18^a and seals the bowl and the operation proceeds over again.

Some of the operating liquid issuing from said leakage holes 40^a, is caught in the trough 60 and flows through openings 45 to the cotton waste of bearings 3 and lubrication is effected as before, the balance of the liquid and any surplus from trough 60 is caught in trough 25^a and carried away by pipe 26^a, all as described for Fig. 1. If the operating liquid is not suitable for lubrication the said holes 45 and the raised flange forming said trough 60 may be omitted and ordinary means of lubrication substituted.

I prefer to place a stop 51^a on pipe 21^a, 40 to limit the upward motion of piston 14^a.

With the class of materials for which the form of machine shown in Fig. 2 is designed filter 11^a may gradually clog up and require occasional washings. This is performed 45 without stopping the rotation of the machine, in the following manner: When said piston 14^a and cover 17^a are in the highest position, the concentrated solids having been discharged, valve 20^a is allowed to remain 50 open, thus keeping the cover in its high position; the valve 34^a is then opened, allowing wash water to pass through pipe 62 into upper inlet 63 of cover 17^a. The first water entering said inlet 63 passes by pipe 64 to valve casing 65 and presses by centrifugal force on valve 66, (which is normally held open against the centrifugal force due to its own mass by the spring 67), and moves said valve 66 radially outward and closes 55 the outlet nozzle 42^a. The water slowly passes out through the leakage hole 68 in valve 66, and said valve 66 remains closed as long as the water admitted from pipe 62 is in excess of the leakage through hole 68. If valve 34^a is now opened wider the

excess water passes into the chamber in the cover 17^a above the filter 11^a, fills said chamber and exerts by its centrifugal force a pressure on filter 11^a, and a flow through said filter in a reverse direction to the regular flow, thereby cleaning said filter of particles clogging its under surface. The water thus forced through the filter passes out through the open discharge for solids into trough 27^a, from whence it may be drawn off in any suitable manner, as by plug 69. After said filter is sufficiently washed valves 34^a and 20^a are closed, said piston 14^a and cover 17^a descend, said packing 18^a is compressed and the bowl sealed and the process of separation may be repeated as before described.

Referring to Fig. 3, illustrating a machine with comparatively large bowl, suitable for the clarification of liquids:

With bowls of very large diameter the actuating pistons must be equivalently large if the centrifugal pressure alone of the operating liquid is used to perform the various functions unless a liquid of great specific gravity, such as mercury, is used. In this condition, therefore, it is especially desirable to employ an operating fluid under considerable pressure to perform the said several necessary functions, and I am thereby enabled to use actuating pistons of relatively small dimensions. I may even so increase said external pressure that the centrifugal pressure becomes relatively unimportant, and I may therefore use, when convenient to do so, a gas under compression, such as compressed air, instead of a liquid, but as stated when referring to the machine of Figs. 1 and 2, I prefer to use a lubricating oil. The source of external pressure 105 may be the street water mains, an elevated reservoir, a pressure tank, or any other suitable device; but I prefer, when the actuating liquid is a lubricating oil, to use an accumulator.

The operating liquid is carried from the source of pressure by pipe 58 to the upper end of an inside spindle 57^b, said pipe 58 communicating with the interior of said spindle 57^b by the stuffing box 36^b. The 115 liquid is also carried from pipe 58 by branch pipe 21^b controlled by valve 20^b to a lower spindle 35^b, to which it is connected by stuffing box 38^b. Said interior spindle 57^b fits loosely into the main spindle 6^b carried by the bearing 3^b. Said main spindle 6^b terminates at its lower end in the cylinder head 24^b of the cylinder 9^b, the lower part of which forms the stem 35^b running in bearing 4^b, said cylinder 9^b being supported by the thrust bearing 5^b. The lower end of the interior spindle 57^b is fixed to piston 14^b working in said cylinder 9^b. Attached to said interior spindle 57^b, near its upper end is the movable bottom 15^b, which, by means of ribs 130

16^b, is attached to cover 17^b carrying around its outer circumference an elastic packing 18^b.

In said spindle 57^b are passages 37^b communicating with the space inside of cylinder 9^b above piston 14^b. 39^b is a passage communicating with space in cylinder 9^b below piston 14^b, and terminating above in a nozzle with leakage hole 40^b. I prefer to use but one such passage 39^b and leakage hole 40^b, thickening the cylinder 9^b on the other side in order to effect a balance, but two sets of passages 39^b and leakage holes 40^b placed opposite each other may be used when desirable.

In order to save space I prefer to cast pulley 7^b as part of cylinder 9^b. 11^b is a coarsely perforated screen which serves to prevent the movable bottom 15 from coming in direct contact with the granular filtering material 13^b. 12^b is a fine annular screen to prevent the material of filter 13^b from passing out of the apparatus. Either or both screens 11^b and 12^b may be omitted where the filter material will pack sufficiently to retain itself in place.

The operation of this form of machine is as follows:

The machine being in a state of revolution at its proper speed, the operating liquid under pressure is admitted through valve 61 and pipe 58 to the interior of spindle 57^b and passes through the passages 37^b, pressing on the top of piston 14^b, not only by the pressure induced by the centrifugal force due to the rotation of the machine but also from the added pressure from the pipe 58. Said spindle 57^b is forced down holding down movable bottom 15^b, and by means of rib 16^b and cover 17^b, compressing the packing 18^b and sealing the bowl around the rim 19^b.

Valve 34^b is now opened admitting the mixture of the granular filtering material 45 and a liquid, such as sand and water, and this mixture passes into the bowl and through the coarse screen 11^b, the liquid passing through screen 12^b and out of circumferential aperture 42^b into trough 22^b 50 and being carried off by pipe 23^b, thence by suitable branch pipes and valves it may be led away to any point desirable. The granular material 13^b is retained and packs in the chamber outside of screen 11^b, until the 55 space is full, forming a uniform filtering body. Said filter 13^b may consist of sand, or may consist of an outer layer of charcoal covered with a layer of sand or any other suitable materials. To insure a proper 60 amount of filtering substance an excess may be run into the machine so that the excess remains on the inside of the screen 11^b. When the desired quantity has been run in valve 34^b is closed. Valve 20^b may be opened 65 admitting operating liquid under pressure

to the underside of piston 14^b in excess of the amount which will flow through the leakage hole 40^b, until the space below the piston 14^b is filled, when by reason of the greater effective area of the underside of said piston 14^b, said piston then rises, carrying with it the movable bottom 15^b, and cover 17^b, and ejects over the rim 19^b any surplus of filtering material. Valve 20^b is then closed, the liquid under piston 14^b escapes through said leakage hole 40^b, the pressure on top of piston 14^b drives down the spindle 57^b and closes cover 17^b as before, and the machine is ready for its work. The supply of liquid to be clarified is then admitted by valve 33^b through pipe 31^b and nozzle 32^b, passes through screen 11^b and filtering material 13^b out of apertures 42^b to trough 22^b, and is led away by pipe 23^b to any point desired. This operation continues until the solid materials collected on the said filter 13^b and inside of screen 11^b have accumulated to such a degree as to require removal. Valve 33^b is then shut off and valve 20^b opened, as before described. Piston 14^b now rises as before described, raising cover 17^b and ejecting said solid materials by means of the movable bottom 15^b. Said solid materials are thrown by the centrifugal force into trough 27^b, whence they may be removed by any suitable means, as by scraper 30. Valve 20^b is then closed, piston 14^b descends as before described, sealing the bowl by means of packing 18^b. Valve 33^b is again opened and the process proceeds as before. When, in the course of time, it becomes necessary to change filtering material 13^b the machine is stopped, the rim 19^b removed by loosening the bolts and the filtering material 13^b removed. Rim 19^b is then replaced, the machine started up and the whole operation repeated as before described. At each downward movement of said piston 14^b the liquid in cylinder 9^b underneath said piston is ejected with great velocity through leakage hole 40^b and strikes against the top of frame 2^b and is deflected into trough 25^b. A portion of this liquid passes through pipe 45^b into bearing 3^b where it is soaked up by the cotton waste in bearing 3^b, and lubricates said bearing. The balance of the operative liquid from trough 25^b flows through hole 26^b on to shield 47^b, which serves to keep the liquid from the belt 8. From said shield 47^b it passes through holes 48^b to the trough 50^b, thus lubricating bearing 4^b, and is conveyed by pipe 49^b to a suitable pump and returned to its original source.

The liquid which has lubricated bearing 3^b, and escapes from that bearing falls on cylinder head 24^b, and is thrown by the centrifugal force from said cylinder head 24^b on to shield 47^b, from whence it runs to trough 50^b, as before described.

Obviously the arrangement of filters and valves described in connection with Figs. 1 and 2, may be used with the relatively small operating cylinder and piston as shown and 5 described in connection with Fig. 3, and the clarifying bowl with granular filtering material of Fig. 3 may be used with the piston and cylinder of Fig. 1, and other interchanges readily suggest themselves.

10 In the description heretofore given, it has been assumed that the various steps described, depending upon the opening and closing of valves, such as 20, 23 and 34 in proper sequence, may be performed manually, and this is preferable until the characteristics of the particular materials to be separated are determined. However, after 15 the proper rate of flow of the materials to be separated and the proper sequence and duration of the various steps have been found, the operations may preferably proceed automatically by means of suitable timing apparatus, arranged to open and close the controlling valves. The timing apparatus may 20 be of mechanical construction, operating the valves by such means as weights, levers and rods, but I prefer to use electrical devices on account of their much greater convenience. Also, instead of operating said valves 20, 33 25 and 34, or their equivalents, automatically. I prefer to use them as adjusting valves to regulate the rates of flow and to introduce additional valves to be automatically opened and closed. Fig. 3, shows a form of machine requiring but two valves, 20^b and 33^b, for its normal operation, valve 34^b only being used occasionally, and I therefore describe the timing apparatus in connection 30 with this figure on account of the greater simplicity of its operation, though as will be readily understood from the following description, such timing apparatus may be applied to the more numerous movements required by those forms of machines illustrated in Figs. 1 and 2, or in fact to any 35 desired number of movements.

Referring to Fig. 3, 75 is a valve, preferably a balanced valve, on pipe 21^b, which is normally held closed by the weight of 40 the solenoid core 76, and 77 is a valve on pipe 31^b, which is normally held open by the weight of the solenoid core 78. The coils of the solenoids 79 and 80 are respectively connected with magnet switches 82 and 83, which are normally open, but which when 45 closed complete the circuit through the solenoid coils with line wires 84 and 85, which carry an electric current of proper strength to operate said solenoids. Said switches 82 and 83 are operated by auxiliary magnets 50 88 and 89, the coils of which are in circuit with the timing apparatus, Figs. 4 and 5, and a suitable source of electricity such as battery 90, Figs. 4 and 5.

Referring particularly to said Figs. 4 and 5, 91 is a shaft which is caused to revolve at a constant speed by any suitable means, such as the gears 92 and 93, worm and wheel 94 and 95 and motor 96; the arrangement of the gearing and speed of the motor being such that the shaft 91 shall make the revolution in the time required for one complete cycle of movements of the centrifugal separator.

Said shaft 91 is supported in standards 75 97 and 98 preferably mounted on a base 99 of suitable insulating material, and said shaft 91 is placed in circuit with said battery 90 by any suitable connection, such as wire 100, to said standard 98. 101 and 102 80 are arms carried by said shaft 91, and which may be placed in any relative position desired and secured by set screws 103 and 104. 105 and 106 are contact plates secured to base 99 in a position to be touched by arms 85 101 and 102 as said arms rotate with shaft 91.

Contact plate 105 is connected by wire 107 with auxiliary magnet 89, Fig. 3, and contact plate 106 is connected by wire 108 with auxiliary magnet 88, Fig. 3, wires 109 90 and 110 completing the circuit with battery 90.

The operation is as follows:—The machine (Fig. 3) being in normal operation, valves 20^b and 33^b having been previously 95 adjusted for the proper rate of flow, and all electric circuits, except motor circuit being open, and therefore valve 77 open and valve 75 closed, the liquid to be clarified flows 100 through valves 77 and 33^b, and nozzle 32^b into the bowl 10^b, the liquid passing through 105 filtering material 13^b, and the solids remaining on said coarse screen 11^b, as before described. This operation continues until arm 101 touches contact plate 105, thus closing 105 the circuit of auxiliary magnet 89 and battery 90. Magnet 89 is energized, lifts switch 83, thus completing the circuit through solenoid coil 80. Core 78 now lifts and closes valve 77, shutting off the supply of liquid 110 to be clarified to the bowl.

After a suitable interval of time, determined by the angular space between arms 101 and 102, during which any remaining liquid in the bowl passes out through filter 115 13^b, arm 102 touches contact 106, energizes auxiliary magnet 88, and in turn solenoid 79 lifts core 76 and opens valve 75, allowing operating liquid to pass to underside of piston 14^b, as before described, and raises said piston and cover 17^b, and the movable bottom 15^b, and ejects the solid materials as hereinbefore described.

After an interval of time, determined by 120 the length of contact plate 106, the arm 102 passes off of said plate 106, breaks the circuit, switch 82 falls, breaking the circuit through solenoid 79, valve 75 closes, piston

14° descends, and the bowl is again sealed, as before described. During this operation arm 101 is still in touch with contact plate 105 and valve 33^a is held closed. After a suitable interval of time, determined by the length of contact plate 105, arm 101 passes off of said plate 105, breaks the circuit through auxiliary magnet 89 and solenoid 80, valve 77 opens and again admits the liquid to be clarified to the bowl, and continues to do so until said arm 101 has revolved with shaft 91, and again comes in contact with plate 105, when the operations described are repeated.

15 The primary current can be carried directly through the timer, and the auxiliary battery and magnet switches dispensed with, when a light current is sufficient to operate the solenoids. With large valves and high operating pressure a heavier current will usually be required than is desirable to pass through the timer contacts, and I prefer in such cases to use a light auxiliary current and magnet switches as shown and described. Obviously by making shaft 91 of suitable length any desired number of arms and contact plates may be used, and any desired number of functions performed, the relative time of each being determined by the angular position of the arms on the shaft, and the relative duration of each function determined by the lengths of the corresponding contact plates. With machines similar to that illustrated in Fig. 1, three sets of arms and contact plates would be required, and the third arm and contact plate being shown in dotted lines in Figs. 4 and 5, one to operate each of the three solenoid valves 20^E, 33^E and 34^E in Fig. 1.

40 In some processes of separation it is not necessary to obtain the separate solids in a dry state, or to perfectly clarify the separated liquid, and in such cases simple decantation is sufficient. In such cases a simple form of machine may be used, without filters and without a cover to the separating vessel. These simpler machines may be constructed in general accordance with the modifications of the separators hereinbefore described. For sake of simplicity of illustration and description, I have preferred to illustrate in Fig. 6, such simpler machine constructed in general accordance with the machine illustrated in Fig. 2, and hereinbefore described. Referring to said Fig. 6, an imperforate bowl 10° without cover or filter, is used. The movable bottom 14° is substantially similar to the movable bottom 14° shown in Fig. 2, and the valves and connections also are similar, except that in this form I prefer to connect pipe 21° to the lower end of spindle 6°.

Said imperforate bowl 10° is preferably of cylindrical form for the major portion

of its height, and is of conical form at the top. During separation the decanted liquid spills over the top edge 19°, and is caught by the shield 8 of the hood S, which is raised to the position shown by the dotted lines. When a sufficient quantity of the separated solids accumulated on the inner periphery of said bowl 10°, the hood S is lowered to the position shown by the solid lines, valve 20° is opened and the separated solids are ejected from said bowl as described in connection with Fig. 2. Obviously when valve 20° is closed and the liquid under movable bottom 14° is allowed to escape through leakage holes 40°, said bottom 14° will descend by gravity, if sufficiently heavy to overcome the frictional resistance of packing 41°, and in this case, said leakage holes 40° could be placed directly in the bottom of said bowl 10°, and the trapped pipes 56° could be dispensed with. But I prefer to use said trapped pipes 56° to induce a vacuum under said bottom 14°, to better overcome the frictional resistance of said packing 41°.

Obviously the stroke of said movable bottom 14° is limited to the cylindrical portion of the bowl, and therefore an amount of solids equivalent to the volume between the piston in its upper position and top of the conical part of the bowl always remains in the machine.

I do not confine myself to the precise forms of centrifugal apparatus or to the precise form of timing apparatus shown and described, but consider that any form of centrifugal machines in which the outlet for the discharge of the heavier concentrated materials is closed by a member controlled by the pressure in a fluid, and any form of centrifugal machine in which the ejection of the heavier materials is effected during rotation by a member controlled by the pressure in a fluid, and any form of centrifugal machine of which the functions described are controlled by automatic timing apparatus to be included within my invention.

Now having described my improvements, I claim as my invention.

1. The method of effecting the separation of solid particles from liquids consisting in supplying operating fluid to a rotary vessel provided with an outlet for separated solids, whereby the pressure of said operating fluid closes said outlet, then supplying the mixture to be separated to said vessel, varying the pressure of the operating fluid in harmonious relation to the separation of the solids from the mixture, whereby the outlet for the discharge of solids from said vessel opens at proper intervals, discharging said solids from said vessel, again varying the pressure of said operating fluid in such manner as to again close said outlet, and so on in continuous ordered succession.

2. The combination in a centrifugal machine of a rotary vessel for the mixture to be separated provided with an outlet for the separated solids, and fluid operated means for positively holding said outlet closed and for opening and closing the outlet for solids at proper intervals. 65
3. The combination in a centrifugal machine of a rotary vessel for the mixture to be separated provided with an inlet for the supply of said mixture and with outlets for the separating liquid and solids, a cylinder and a piston therein operatively connected with the outlet for solids and adapted to be 70 actuated by a fluid to positively hold said outlet closed and to open and close said outlet at proper intervals.
4. The combination in a centrifugal separator of a separating vessel having a cover and ejector rigidly connected together and fluid operated means to hold said cover closed during separation and to open said cover and actuate said ejector after separation. 75
5. The combination in a centrifugal machine of a rotary vessel for the mixture to be separated provided with separate outlets for the separated liquid and solids, fluid operated means for opening and closing said outlet for solids, valves and electrically operated means for opening and closing said valves at proper intervals and in proper relation to the operation of said machine in separating the solid and liquid constituents of said mixture. 80
6. The combination in a centrifugal machine of a rotary vessel for the mixture to be separated provided with separate outlets for separated liquids and solids, and fluid operated means for opening and closing said outlet for solids and for ejecting said solids from said vessel automatically at proper intervals. 85
7. The combination in a centrifugal machine of a rotary vessel for the mixture to be separated provided with separate outlets for separated liquid and solids, a cylinder and a piston therein adapted to be operated by a fluid to open and close said outlet for solids and to eject said separated solids from said vessel automatically at proper intervals. 90
8. The combination in a centrifugal machine, of a rotary vessel for mixture to be separated provided with separate outlets for the separated liquid and solids, means for ejecting the separated solids from said vessel, a cylinder and a piston therein operatively connected with said means, and adapted to be operated at proper intervals by a fluid, whereby said outlet for solids is opened and closed, and said solids are ejected automatically at proper intervals. 95
9. The combination, with the separating vessel of a centrifugal machine, of a movable cover, a piston operatively connected with said cover, and means for reversing fluid pressures on said piston for opening and closing said cover. 100
10. The combination, with the separating vessel of a centrifugal machine, of a movable cover for said vessel, an ejector for separated solids, a piston operatively connected with said cover and ejector and means for varying fluid pressures on said piston for holding said cover closed during separation and for opening said cover and actuating said ejector after separation. 105
11. The combination in a centrifugal machine of a rotary separating vessel, a cover therefor adapted to be operated by the pressure of a liquid, and lubricating devices adapted to cause said liquid to lubricate said machine. 110
12. The combination in a centrifugal machine of a rotary separating vessel, means operated by fluid pressure to eject the separated solids from said vessel and devices adapted to cause said operating fluid to lubricate said machine. 115
13. In a centrifugal machine the combination of a rotary separating vessel, a movable cover therefor, an ejector for separated solids, fluid operated means for actuating said cover and ejector, and devices adapted to cause said operating fluid to lubricate said machine. 120
14. The combination in a centrifugal machine of a rotary separating vessel, a movable cover therefor, and means operatively connected with said cover and adapted to be actuated by centrifugal pressure induced in a liquid by the rotary motion of said machine. 125
15. The combination in a centrifugal machine of a rotary separating vessel, an ejector for discharging the separated solids from said vessel, and means operatively connected with said ejector and adapted to be actuated by centrifugal pressure induced in a liquid by the rotary motion of said machine. 130
16. The combination in a centrifugal machine of a rotary separating vessel, a movable cover therefor, an ejector for the discharge of separated solids from said vessel, and means operatively connected with said cover and ejector adapted to be actuated by centrifugal pressure induced in a liquid by the rotary motion of said machine. 135
17. The combination in a centrifugal machine of a rotary separating vessel, a movable cover therefor and devices operatively connected with said cover adapted to be actuated by fluid pressures additional to the fluid pressure induced by centrifugal force. 140
18. The combination in a centrifugal machine, of a rotary separating vessel, a mov-

able cover therefor, an ejector for discharging the separated solids from said vessel and devices operatively connected with said cover and said ejector and adapted to be actuated by fluid pressures additional to the fluid pressure generated by centrifugal force.

19. The combination in a centrifugal machine, of a rotary separating vessel, an ejector for discharging separated solids from said vessel and devices operatively connected with said ejector and adapted to be actuated by fluid pressure in addition to the fluid pressure generated by centrifugal force.

20. In a centrifugal machine the combination of a separating vessel, a cover, and means adapted to be operated by a liquid other than that undergoing separation to maintain said cover closed during separation and to discharge said vessel after separation.

21. The combination in a centrifugal machine of a separating vessel, means to maintain said vessel closed against escape of the mixture during separation and to discharge the separated solids from said vessel after separation adapted to be actuated by pressure of a fluid, valves to control said fluid, and automatic devices for governing the times of opening and closing said valves.

22. The combination in a centrifugal machine, of a separating vessel, means to maintain said vessel closed against escape of the mixture during separation, means to discharge the separated solids from said vessel after separation, and automatic electric devices for controlling the duration of said separation and time of said discharge.

23. The combination in a centrifugal machine, of a separating vessel, means to maintain said vessel closed against escape of the mixture during separation, means to discharge the separated solids from said vessel after separation, and automatic devices for controlling the duration of said separation and time of said discharge.

24. The combination in a centrifugal separator, of a separating vessel, a cover therefor, and means operated by liquid pressure to hold said cover closed against the pressure of the mixture which is undergoing separation.

25. The combination in a centrifugal machine of a rotary vessel for the mixture to be separated, a movable cover provided with an elastic packing adapted when closed on said vessel to seal the outlet for separated solids, and fluid operated means to actuate said cover.

26. In a centrifugal machine the combination with a separating vessel having an outlet for the separated solids of a movable cover, an elastic packing therefor, and fluid

operated means to compress said packing, seal said outlet and hold said cover closed against the pressure of the mixture undergoing separation.

27. The combination in a centrifugal separator having relatively movable parts, of a cylinder and piston operatively connected with said parts, a continuous operative pressure on one side of said piston and means to vary fluid pressure on the other side of said piston.

28. In a centrifugal separator having an operating cylinder and piston, a continuous operative pressure on one side of said piston, a leakage hole in said cylinder and a valve to control the supply of operating fluid to the other side of said piston.

29. In a centrifugal separator having a separating vessel with a movable cover, a cylinder and piston operatively connected with said cover, a continuous pressure on one side of said piston and means to vary the pressure on the other side of said piston and actuate said cover.

30. In a centrifugal separator having a movable member adapted to eject the separated solids, a cylinder and piston operatively connected with said movable member, a continuous pressure on one side of said piston and means to vary the pressure on the other side of said piston and reciprocate said movable member.

31. The combination in a centrifugal separator having relatively movable parts of a cylinder and piston operatively connected with said parts, and a leakage hole for the exhaust of the operative fluid from said cylinder.

32. The combination in a centrifugal separating vessel having an outlet for the separated solids, of a cover adapted to close said outlet in a direction opposite to the pressure of the separating mixture and fluid operated means to close said cover.

33. The combination in centrifugal separator of a separating chamber, a movable cover therefor, an ejector for the separated solids, a cylinder and piston, a continuous pressure on one side of said piston and means to vary the pressure on the other side of said piston and actuate said cover and ejector.

34. The combination with a centrifugal separator of a separating chamber, an ejector therein adapted to eject the concentrated solids, a cylinder and piston operatively connected with said ejector, a continuous pressure on one side of said piston, a leakage hole in said cylinder and a valve to vary the supply of actuating fluid to said cylinder and actuate said ejector.

35. The combination in a centrifugal separator having relatively movable parts of fluid actuated means operatively connected

with said parts and leakage holes for the exhaust of said actuating fluid.

36. In a centrifugal machine having relatively movable parts, means operatively connected with said parts adapted to be actuated by fluid pressure additional to the fluid pressure induced by centrifugal force.

37. The combination in a centrifugal machine, of a rotary separating vessel, an ejector for discharging the separated solids from said vessel, and actuating means operatively connected with said ejector and adapted to be actuated by centrifugal pressure induced in a liquid by the rotary motion of said machine.

38. In a centrifugal machine, the combination with a bowl and an ejector, relatively movable to each other, of actuating means operatively connected to one of said parts for moving the same relatively to the other and adapted to be actuated by centrifugal pressure induced in a liquid by the rotary motion of said machine.

39. In a centrifugal machine, the combination with a bowl and ejector therefor, relatively movable to each other, of means for actuating one of the said members relatively to the other by centrifugal pressure

induced in a liquid by the rotary motion of said machine.

40. The combination in a centrifugal machine, of means for supplying fluid thereto to be separated, means to supply to said machine an operating fluid other than that undergoing separation, and parts adapted to be moved away from each other by the centrifugal pressure induced in said operating fluid by the rotation of said machine.

41. In a centrifugal machine the combination with members relatively movable to each other, and with means to supply fluid thereto to be separated, of means for supplying to said machine an operating fluid other than that undergoing separation, and means for moving said members away from each other by centrifugal pressure induced in said operating fluid by the rotary motion of the machine.

Signed at New York city, in the county of New York, and State of New York, this 20th day of April, A. D. 1914.
